ATTORNEY

UNITED STATES PATENT OFFICE

JOHN PELLONI, OF ELLWOOD CITY, PENNSYLVANIA

AUTOMATIC ALARM SIGNAL

Application filed August 22, 1928. Serial No. 301,366.

This invention relates to alarm signal systems for use within dwellings and the like for signalling the presence of fire or the attempt at house-breaking.

5 An object of the invention contemplates the provision of annunciators operable by both temperature and contact whereby fires and attempted burglaries may be detected.

Another object of the invention comprehends an operating mechanism whereby the receiver upon a telephone may be lifted, a phonograph started and a bell rung whereby the occupant of the house and the fire chief may be notified of the fire.

15 More specifically stated the operating mechanism is provided with a holding element whereby the device may be supported while being reset.

With the above and other objects in view, 20 the invention further consists in the following novel features and details of construction, to be hereinafter more fully described, illustrated in the accompanying drawings and pointed out in the appended claim.

25 In the drawings:—

Figure 1 is a vertical sectional view taken through my invention.

Figure 2 is a top plan view of the phonograph and telephone.

30 Figure 3 is a detail sectional view taken through the operating mechanism.

Referring to the drawings in detail, wherein like characters of reference denote corresponding parts, the reference character 10 indicates a cabinet within which a phonograph 11 and telephone 12 are supported. The speaker 13 for the phonograph is adapted to face the telephone transmitter 14, the purpose of such arrangement will be presently 35 apparent.

The operating mechanism includes a cylinder 15 having a bottom 16 and within which a plunger or piston 17 is mounted for reciprocating action. The plunger or piston shaft 18, upstanding from the piston, is projected within the core 19 of a solenoid coil 20.

A fusible element 21, preferably stretched across the ceiling or wall of a room or a series of rooms, is passed over a pulley wheel 21' 50 and extended within an opening 22 in the

solenoid coil 20 for connection with a ring 23 upon the free end of the plunger shaft 18. Such arrangement normally supports a piston or plunger 17 to occupy the position shown in Figure 1 of the drawing.

55

A cable 24, having connection with the upper side of the plunger or piston 17, is passed over pulleys 25 and 26 whereby the same may be disposed directly above the telephone receiver 27, whereby the cable when connected therewith will effectively lift the receiver when the piston is lowered. By the same token, the cable 28, also having connection with the piston 17 and passed over the pulley wheel 25 and a separate pulley 29, is connected with a switch arm 30 for the phonograph 11, whereby the telephone receiver 27 and phonograph 11 will be simultaneously set in motion. The record upon the phonograph is adapted to inform the fire and police chiefs 60 of the burning of the fusible element by reason of the fact that the telephone transmitter 14 faces the speaker 13 but it may also be desirable to inform the occupants of the house as well, and in this instance an annunciator 65 in the nature of a bell 31 is employed.

70

Said bell is adapted for connection in circuit with a step-down transformer 32 through the instrumentality of a conducting wire 33, whereas its opposite pole is connected with a 75 switch member 34 through a lead 35. The switch 34 is in turn connected with a stationary portion 36 of a knife switch 37 through a conducting wire 38. The knife 37 is adapted for direct connection with the transformer 80 32 through a wire 39. Obviously the transformer is energized from the house current and this is accomplished through cables 40 and 41 respectively. The wires 38 and 39 respectively are in turn connected with wires 85 42 and 43 having connection with contact members upon window frames which when brought into contacting engagement by the raising of a window will ring the bell 31 irrespective of the presence of the knife 90 switch 37.

A spring latch finger 44, operating within a sleeve member 45, is adapted for connection at its uppermost end with a cable member 46 passed over pulleys 47 and 48 respec- 100

tively for subsequent connection with the upper side of the piston or plunger 17 in oppositely disposed relation to that of the cables 24 and 28 respectively, substantially as illustrated in Figure 1 of the drawings. The lowermost end of the spring operated latch finger 44 is normally adapted for contacting engagement with the free end of the knife switch 37 which is normally induced thereagainst by a retractile spring 49.

When the occupants of the house leave, for any purpose, the switch 34 may be opened to break the circuit between a stationary portion of the knife switch and the bell, whereby the latter will be rendered ineffective and the burglar will not be scared off.

After the fusible element 21 has been broken by the temperature created by a fire, the plunger or piston 17 will drop and actuate the phonograph, phone, and bell.

After the stylus arm 50 for the phonograph has traveled a given distance across the record therefor, a contact member 51 carried thereby is adapted to engage a contact member 52. The contact 51, carrying a lead wire 53, is adapted for connection with a contact member 54 located in the path of movement of an oscillating head 55. The other contact 52 carries a lead wire 56 which is connected to one side of the step-down transformer 32 to a lead wire 57 and the house current. The head 55 is carried upon a shaft member 58 operable within a housing 59 having communication with the cylinder 15. A lead wire 60 establishes connection between the head 55 and the solenoid coil 20. A push button switch 61, connected in circuit with the lead wires from the house current, is adapted to energize a solenoid coil 62 whereby the core 63 therefor may be actuated simultaneously in conjunction with a shaft member 64 having connection with the shaft member 58 for the head 55 through the instrumentality of an arm 65. The shaft member 64 is in addition adapted for connection at its free end with a knife switch 37.

As illustrated, one lead from the transformer and house current is adapted for connection with the solenoid coil 20.

The push button 61 and solenoid coil 62 and rod 64 therefor are called into use to retract the shaft member 58 from the position shown in Figure 3 of the drawings after the contact has been established between the contact members 51 and 52 respectively for raising or elevating the piston 17 within the cylinder 16. The relative arrangement of the shaft member 58 and piston or plunger 17 in the Figure 3 position facilitates repairing or replacement of the fusible element 21.

After the element has been replaced the push button 61 is then depressed to shift the shaft member 64 whereby the knife switch 37 may be opened and the shaft member 58 retracted to release the plunger or piston 17.

The invention is susceptible of various changes in its form, proportions and minor details of construction, and the right is herein reserved to make such changes as properly fall within the scope of the appended claim. 70

Having described the invention, what is claimed is:—

An apparatus of the character described comprising a normally inoperative phonograph, a normally inactive telephone arranged to dispose the transmitter therefor in juxtaposition to the speaker of the phonograph, a cylinder, a weight member slidably mounted within the cylinder having operative connection with a telephone receiver and phonograph brake to effect simultaneous operation thereof, a solenoid disposed adjacent said weight, a plunger shaft for the weight slidably arranged within the core of the solenoid, a local annunciator, a switch member located adjacent and normally held in open circuit with the annunciator by the weight, a shaft member carried by and extended through the cylinder for frictional engagement with the adjacent surface of the weight member therein, a contact included upon the shaft member in oppositely disposed relation to that of the weight, a stationary contact arranged in the path of movement of and normally frictionally engaging the contact upon the shaft member, and spaced contacts included upon the phonograph and tone arm therefor being designed for ultimate contacting engagement to retract the weight member, brake the phonograph and replace 100 the telephone receiver subsequent to the phonetic and annunciator signals. 85

In testimony whereof I affix my signature.
JOHN PELLONI.
